UNITED STATES PATENT OFFICE.

ZACHARY T. FRENCH AND WILLIAM C. MEYER, OF BOSTON, MASSACHUSETTS,
ASSIGNORS TO THE GOODYEAR SHOE MACHINERY COMPANY, OF HARTFORD, CONNECTICUT.

SEWING-MACHINE.

SPECIFICATION forming part of Letters Patent No. 412,703, dated October 8, 1889.

Application filed November 23, 1887. Serial No. 255,975. (No model.)

To all whom it may concern:

Be it known that we, ZACHARY T. FRENCH and WILLIAM C. MEYER, both of Boston, county of Suffolk, and State of Massachusetts, have invented an Improvement in Sewing-Machines, of which the following description, in connection with the accompanying drawings, is a specification, like letters on the drawings representing like parts.

10 This invention relates to improvements in that class of wax-thread sewing-machines employing a curved needle, curved awl, and a nearly circular oscillating shuttle; and our invention has for its object to improve and 15 simplify such class of machines in order that the stitch may be better and more uniformly made, the needle-thread required for each succeeding stitch being automatically measured off or taken in advance from a thread- 20 supply in varying quantity, according to variations in the thickness of the stock.

Our improved machine is provided with a clamp and a pull-off to act directly upon the needle-thread, the pull-off acting, while the 25 said thread is clamped, to thus take from a tension device or the thread-supply a variable amount of thread for the needle, and hence called "needle-thread," and the said pull-off is so constructed as to enable the cross- 30 ing or locking point of the two threads used to be drawn into the sole or stock, or into a channel therein for a uniform distance from its outer side, notwithstanding variations in the thickness of the sole or stock.

35 In our invention the needle-thread taken from the thread-tension or a thread-supply, which may be a suitable spool, ball, or cop, is acted upon by a clamp and a pull-off before it is passed through the eye of the looper to 40 be supplied to the hook of the hooked needle, the said clamp being located between the pull-off and the take-up, which is employed to take up the loop of thread cast off from the shuttle, the clamp, as herein shown, acting to clamp and hold the said needle-thread 45 at a point between the take-up and the thread-supply twice during each stitch. The needle-thread is clamped once, or between the pull-off and needle, while the pull-off acts upon the

thread to draw from the thread-supply a sufficient quantity of needle-thread to form the next stitch, the movement of the pull-off at such time being variable according to the thickness of the stock, the clamp preventing the thread supplied for the previous stitch 50 from being drawn back, and at this same time the take-up acts to draw up the loop of needle-thread cast off from the shuttle, and to set the stitch. The stitch having been set and a sufficient quantity of needle-thread having 55 been pulled off for the next stitch, the clamp changes its position and clamps the thread between the pull-off and the needle-thread supply, and then the pull-off commences to rise, and at such time an auxiliary take-up, to 60 be described, also rises through the action of a suitable spring, thus taking up the needle-thread given up by the pull-off while the clamp held the needle-thread between the pull-off and thread-supply, the said auxiliary take-up 65 preventing any retrograde movement of the needle-thread, while the clamp again changes its position preparatory to pulling off a second portion of needle-thread, the said auxiliary take-up thereafter giving up the needle-thread stored up or held by it to the stitch-forming devices. The pull-off is operatively connected with the work support or table through a variable-motion mechanism, whereby the pull-off has more or less movement im- 70 parted to it through changes in position of the said work support or table, the position of the latter being determined by the thickness of the stock. The said variable-motion mechanism is provided with means to control the extent to which the locking or cross- 75 ing point of the two threads may be made to sink into the outer sole or stock, the said crossing-point being at a definite distance from the outer side of the sole or the upper 80 side of the stock, whatever may be the thickness of the said sole or stock.

In the machine herein to be described, wherein a sufficient quantity of needle-thread is positively and automatically drawn off from the thread-supply before the commencement of the stitch next to be made, it will be understood that the shuttle when entering the 85 90 95

loop of needle-thread does not and need not subject the said needle-thread to a strain such as would tend to cause the previous stitch to be unduly embedded into and to the injury 5 of the under side of the stock, or to the welt, which, when our machine is used to stitch a welted shoe, rests on the work support or table.

The looper herein to be described has im- 10 parted to it two motions, one of reciprocation and the other a slight rocking motion, by peculiar mechanism to be described.

We have provided a hook to co-operate with the looper, the said hook receiving upon 15 it a needle-thread during the movement of the looper around the needle, the said hook acting to hold the needle-thread while the looper passes or crosses the path of movement of the hooked needle at its hooked side to lay 20 the needle-thread into the hook of the needle just before the needle rises.

To prevent the loop of needle-thread cast off from the shuttle from getting in the way of the needle, we have provided a loop-guide, 25 the same being located near that part of the shuttle-race where the loop is discharged, and having its delivery end terminating near the surface of the stock.

Figure 1 is a right-hand-side elevation of a 30 sufficient portion of a sewing-machine containing our improvements to enable the same to be understood; Fig. 1^a, an enlarged perspective of the loop-expander 147. Fig. 2 is a top or plan view of the machine shown in 35 Fig. 1; Fig. 3, a front elevation thereof; Fig. 3^a, a detail showing the shoe c⁸ detached and a section of it; Fig. 4, a left-hand-side elevation of the machine shown in Fig. 1. Figs. 5 and 6 represent in elevation and section 40 our improved shuttle. Fig. 7 is a section of the machine shown in Fig. 3 on the line x x, looking toward the left. Fig. 8 is a detail of the looper and its actuating mechanism. Fig. 8^a is a diagram showing a part of the hooked 45 needle and looper and thread, the dotted lines showing the direction of the movement of the looper when supplying the needle with thread. Fig. 9 is a section in the line x' x' of Fig. 8. Figs. 10, 11, and 12 represent details of the 50 shuttle race and driver with its connected pad and of the driver and pad; and Fig. 13 is a detail chiefly to show the awl-carrying segment and the actuating device therefor.

The column A has bolted to it at its upper 55 end a plate A', which receives the pivots or studs for the pull-off, the take-up to be described and rocking hub carrying the clamp 5, the studs for the rolls 3, 4, and the stud 36, on which turns the roll n¹³ and the auxiliary 60 take-up. The plate A' has bolted to it the bottom plate of the head A², it having uprights A¹² to form bearing for the main shaft A³, and other uprights to form bearings for other working parts. The shaft A³ is or may be 65 driven by power applied to the wheel A⁴. The shaft A³ has fast upon it near its right-hand end a cam b, having a groove 6, which

receives in it a roll e at the end of a slotted lever f, pivoted at 7 on a fixed part, as g, of the head of the machine, the said lever embracing a stud h, erected on a horizontally-extended part of a feed-carriage j, the vibration of the said lever causing the said carriage to be reciprocated in a guideway in the said bracket g. The carriage j has a stud t, 75 which serves as the fulcrum for the awl-carrying segment s, (see Figs. 1 and 13,) to which is attached the curved awl r. The awl r acts to feed the material as the carriage j is moved horizontally with the awl in the stock. In 80 practice the said segment will be moved as in United States Patent No. 240,307, wherein the parts of the awl-feeding mechanism referred to are designated by like letters.

The carriage j receives in it a bar m, provided at its lower end with a presser-foot and channel-guide m', it bearing on the upper side of the outer sole or stock m², (partially shown in Fig. 1 as resting on the work support or table 15,) a projection or lip of the 90 said foot entering a channel cut in the usual manner in the outer sole. The upper end of the bar m has a roller or other stud, which is embraced by the slotted end of a lever m', pivoted on a stud m^x, (see dotted lines, Figs. 95 1 and 2,) the rear end of the said lever having a roller m⁵, which is acted upon by a periphery of a cam c, it being the second cam fast on the shaft A³ from its right-hand end, the said presser always forcing the upper surfaces 100 of the sole or stock down to a predetermined level whatever may be the thickness of the stock.

The segment 18, to which is secured the 105 curved hooked needle 16, is loose on the bolt or stud 19 in the head of the machine, it being in line with the stud t. The segment 18 is engaged and moved by the toothed end 21 of the lever 22, pivoted at 23, the said lever having a roller or other stud 23^x, which enters the groove 22^x of the cam-hub d, fast on the shaft A³, it having at its periphery three cam-surfaces 51, o¹³, and o²⁰, to be described.

The hooked needle, its actuating mechanism, and the needle-guide 26, the toothed sector 28, to which it is attached, and which is engaged and actuated by the pinion x on the shaft 29, are also common to the said patent, and so need not be herein more fully described.

The work support or table consists, essentially, of a projection 15, having a slot for the passage of the needle and awl, and of a swing-piece 44, to which the projection 15 is secured, the said swing-piece being pivoted at 45. The work support or table at its lower end has an 125 arm 46, (see Fig. 1,) which enters a slot in a slide-bar 47, the parts 44 45 46 47 being also common to the said patent. Herein the said slide-bar 47 has at its rear end a projection 130 carrying an adjustable screw b', to which is attached a spiral spring b², the opposite end of the spring being attached to a stud b³ on the head A², the said spring normally acting to force the bar 47 forward, so as to keep the

work-support thus made yielding pressed up against the stock. The bar 47 has a series of ratchet-teeth, (partially shown at b^4 , Fig. 1,) which are engaged by two like pawls, one only of which is shown in Fig. 1, mounted upon a lever b^6 , having its fulcrum at b^7 , the upper end of the said lever having a roller or other stud, as b^8 , (see dotted lines, Fig. 1,) which enters a cam-groove at the inner side 10 of the cam b , the said cam-groove operating the said lever to maintain the pawls in engagement with the ratchet-teeth b^4 while the needle acts to penetrate the stock, and also while the take-up, to be described, acts to set 15 the stitch.

The swing-piece 44 has a backwardly-extended arm, to which is jointed at b^9 one end of an adjustable connecting-rod b^{10} , the length of which determines the depth of the 20 crossing or locking point of the threads below the surface of the outer sole, the opposite end of the said rod being jointed or attached, as by a screw c' , to not only a link c^2 , but also to a shoe c^3 , (shown as a block having a dovetail groove,) the shoe being partially broken out in Fig. 3, and shown separately and in section in Fig. 3^a enlarged, the said rod, shoe, and link constituting a variable-motion device. The shoe c^3 is free to 25 slide on one arm c^4 of a rocking hub c^{10} , free to be turned or rocked upon a stud c^5 , attached to a bracket c^6 projecting from the plate A' , the opposite end of the said rocking hub being provided with a roll 2, about which is 30 passed the needle-thread between the roll 3 and the roll 4, the said roll 2 and the said hub and its arms constituting a pull-off to act on the needle-thread to pull off or take from the 35 tension device c^7 of any usual or suitable construction or from the thread-supply, (not shown,) which may be a spool or cop, a sufficient quantity of needle-thread to form the next stitch to be made.

The shoe c^3 by a pin d^1 is joined to a link d^2 , (see Fig. 1,) in turn jointed at d^3 to a lever d^4 , pivoted at d^5 , the upper end of the said lever having a suitable roller or other stud, (shown by dotted lines,) which enters a cam-groove cut in the right-hand side of the 45 cam c , the said cam moving the said lever d^4 uniformly at each rotation of the main shaft A^3 , and should the shoe c^3 remain in position upon the outwardly-extended arm c^4 of the 50 rocking hub c^{10} , carrying the said pull-off, then the amount of thread pulled-off for each 55 stitch would be uniform; but this shoe c^3 is moved more or less vertically upon the said arm c^4 through the connecting-rod b^{10} , attached to the part 44 of the yielding work 60 support or table, and, as will be readily understood, the said work-support, being turned more or less by variations in thickness of the stock m^2 , will move the shoe c^3 in a corresponding manner, so that the said arm c^4 and 65 pull-off will have imparted to them a variable stroke—the nearer the shoe c^3 to the center of motion c^5 of the arm c^4 , carrying the pull-off,

the greater the motion of the pull-off for the next stitch to be made, and vice versa.

To insure a right-line movement for the connecting-rod b^{10} and shoe c^3 , the latter has jointed to it the radius bar or link c^2 , before referred to, it being pivoted at d^7 on the bracket c^6 .

Between the rolls 3 4 is placed a clamp 5 to act directly upon the needle-thread, (see Fig. 7,) attached by a screw 6 to a lug 8, forming part of a rocking hub 9, the upwardly-extended left-hand end of which, viewing the front of the machine, (see Figs. 3 and 4,) receives through it a threaded bolt 10, joined at 30 (see Fig. 4) to the lower end of the lever 31, having its fulcrum at 32, the said rod at each side of the upwardly-extended portion of the said rocking hub having applied 35 to it like adjusting-nuts 12, the said rod being surrounded between the said hub and the said nuts at each side of the said hub with suitable spiral or other springs 13, which act as cushions when the rod 10 is moved horizontally by the lever 31, the said springs at such time acting directly against the upwardly-extended portion of the said rocking hub and enabling the clamp 5 to clamp the thread closely, but yet not pinch it hard 40 enough upon the roll with which it co-operates as to crush or weaken the thread. The lever 31, for moving the rocking hub 9 of the clamp 5, referred to, so that the clamp at one portion of the time during each rotation of the main shaft may clamp the needle-thread w against one of the rolls 4 or 3, and then against the other, as referred to, has at its upper end a suitable roller or other stud 33, (shown by full lines in Fig. 3,) which enters 45 a cam-groove cut in the inner side of the cam e^2 , the said cam-groove being shown by dotted lines at e^3 in Fig. 4. After leaving the roll 4 the needle-thread is passed over a roller 34, (see Fig. 7,) mounted loosely upon a 50 stud at the inner end of a lever 35, (see Figs. 1, 3, and 4,) pivoted at 36, the said lever being acted upon by a spring 37, connected at one end to a fixed arm 38, so that the said spring 55 normally acts to move the roller 34 toward 60 the needle.

The roller 34, lever 35, and spring 37 constitute what we shall call the "auxiliary take-up," its purpose being to prevent any retrograde or back movement of the needle-thread 65 while the clamp 5 moves from the roller 4 to the roller 3, the auxiliary take-up taking up any slack thread which may exist at that time and giving it up subsequently to the main take-up, now to be described.

The main take-up consists of a lever n , having, preferably, at its outer end a roll n' , the said lever forming part of a rocking hub n^2 , supported on a stud n^3 in the plate A' , the said hub at its opposite end having an arm n^4 , which is connected by a short link n^5 with a lever n^6 , having its fulcrum on a stud n^7 of an arm n^8 , projecting from one of the uprights or stands supporting the main shaft A^3 . The 70 75 80 85 90 95 100 105 110 115 120 125 130

upper end of the lever n^6 is provided with a roller or other stud n^9 , which enters a cam-groove n^{10} at the side of the cam-hub e^2 , fast to the main shaft A^3 , the said take-up operating at the proper time to take up the loop of thread cast off from the shuttle D , (to be described,) and draw the needle-thread taut to set the stitch, the take-up at no time acting to draw thread from the thread-supply, 10 but only taking up the thread from the slack made in the needle-thread by or through the action of the pull-off, as described, and held by the auxiliary take-up. The needle-thread between the take-up roll n' and the thread-guide or looper o is passed over a roll n^{13} , mounted upon a stud 36, which serves as the fulcrum for the lever 35 of the auxiliary take-up.

By taking the needle-thread from the thread-supply and tension device through the agency 20 of a pull-off having a variable motion, due to thickness of the stock, and holding the thread so pulled off for the stitch next to be made, and giving it up to the take-up as required, 25 the strain upon the take-up is reduced, and, what is of greater importance, the thread is not acted upon by a strong force between the junction of the thread with the stock and the pull-off.

30 Pulling off from the thread-supply and storing up enough thread for the next stitch to be made makes it unnecessary for the shuttle to draw from the thread-supply during its passage through the loop of needle-thread sufficient thread for the next stitch to be 35 made, and consequently the shuttle does not exert such strain upon the loop of needle-thread as to cause it to be drawn and embedded too far into the welt or into the lower 40 side of the stock to its injury.

40 Adjusting the length of the connecting-rod b^{10} through the right and left threaded nut 40 thereon makes it possible to control the depth to which the locking or crossing points of the 45 needle and shuttle threads shall be drawn below the upper side of the sole or stock upon which rests the presser-foot, the said locking-point being maintained at a uniform distance from the upper surface of the sole 50 next the presser-foot, notwithstanding variations in the thickness of the sole or stock. By shortening the rod b^{10} the stroke of the pull-off may be increased to thereby enable it to pull off from the thread-supply more of 55 the needle-thread, thus giving more thread for the loop of needle-thread, which enables the locking or crossing point of the thread to come nearer the upper side of the stock; but by lengthening the said rod so as to pull off 60 a less quantity of needle-thread to shorten the loop therein the locking or crossing point of the two threads will be brought closer to the under side of the stock.

65 It will be understood that the shuttle thread accommodates itself to the needle-thread, and as the loop of needle-thread varies in length, the length of which may be

controlled as desired, the loop of shuttle-thread is drawn more or less into the stock.

The looper is composed, essentially, of an arm 70 o , having an eye, and an arm o' , having a split hub, as o^2 , which by a screw, as o^3 , is clamped upon the forward end of a sleeve o^4 , mounted in bearings o^5 , the said sleeve at its rear end being provided with an annularly-grooved 75 hub o^6 , in which enters a swivel-block o^7 at the end of a horizontally-sliding link o^8 , pivoted to the lower end of an elbow-lever o^9 , having its fulcrum at o^{10} , the said lever having near its central bent portion a cam-roll o^{12} , 80 which is acted upon by a cam projection o^{13} at the periphery of the cam-hub d , the said roll being kept in contact with the periphery of the said cam by a spring, as o^{14} , attached to the said lever, and to a pin, as o^{15} , erected 85 upon the bearing o^5 . The sleeve o^4 , hollow for the passage through it of the needle-thread, has splined upon it a hub o^x , having a sector o^{16} , which is engaged by a sector-lever o^{17} , pivoted on a stud o^{18} , and provided 90 with a cam-roll o^{19} , which is acted upon by a cam o^{20} at the side of the cam o^{13} , before referred to. The connection between the hub o^x and the sleeve o^4 is such that the latter is free to slide longitudinally through the former, both, however, rocking together. The cam-roll o^{19} is normally kept against the peripheric cam o^{20} of the cam-hub d , referred to, by a spring 42, (see Fig. 4,) resting upon the plate A^2 , the movement of the lever o^{17} by the 95 cam rocking the looper, while the movement of the lever o^9 causes it to be moved horizontally, the combined movements of the looper through the devices or instrumentalities described being such as to cause the delivery-eye at the end of the looper to follow in the path of substantially the shape designated by the dotted-line diagram near its end in 100 Fig. 8^a.

The looper o , starting from the point 43, 110 moves to the left in the direction of the arrow 60 upon the said diagram to the point 44, when it turns aside and travels in a curved path about the hook p , continuing its motion until it reaches the point 45, laying its thread, 115 as shown by the full lines, Fig. 8^a, upon the end of the hook p , the thread being bent about the needle 16 and laid into its hook. The looper having arrived at the point 45, the needle 16 commences to rise, taking with it 120 the thread w , and then the looper starts back along its former path and follows in the direction of the dotted lines (represented by the arrow 47) to the point 43, from which it started, where its movement is temporarily 125 arrested, with its eye in the line or direction of strain upon the thread, it remaining there until the stitch is set, thus obviating undue friction of the needle-thread in the eye of the looper, the awl at such time piercing the stock 130 and feeding the material over the work-support.

The hook p is attached to a hook-holding arm secured to the frame-work by a bolt 46.

(See Fig. 4.) The loop of needle-thread drawn through the material by the hooked needle 16 is caught by the lower hooked end of the spreader 147, (shown separately in Fig. 1^a), the said spreader being connected to a spreader-lever 48, pivoted at 49, the spreader-lever having a roll 50, (see Fig. 2,) which is acted upon by the peripheric cam 51 of the cam-hub *d*, referred to, attached to the main shaft, the said spreader acting to draw up the loop of needle-thread and hold it for the entrance therein of the point 52 of the shuttle D. A spring 53, connected to an arm of the lever 48, and also to a fixed part of the frame, normally keeps the roll 50 in contact with its actuating-cam. The lever 48 receives through it a bolt 54, which is also extended through a slot in an ear 55, extended upward from or forming part of the shuttle-case, the said ear and bolt serving as a guide for the lever 48, to prevent any side motion or vibration thereof.

The shuttle D (shown separately in Figs. 5 and 6) for more than two hundred and seventy degrees is circular, the shell or body of the shuttle having at its outer edge a bearing-rib 56.

The shuttle D receives within it a cop or ball, as 57, of waxed thread, which is drawn from the center of the ball through a hole, as 58, in a lid 59, pivoted at 60 to the shell, the said lid having attached to it by screws 61 a delivery projection or button 62, having a thread-delivery hole 63, located at the center of oscillation of the shuttle, but at one side of the center of the ball, the shuttle-thread 64 being thus delivered from the shuttle directly at its center of oscillation, yet enabling the ball to be made larger and to be formed with but a small central opening, and yet obviate friction of the shuttle-thread upon itself when being drawn from the ball or roll. The shuttle-thread between the said lid and button is acted upon by a tension device 65, shown as a bent spring inserted between the lid and button, one end of the said spring being bent to enter one of a series of holes 66 in the lid, so that the strength of the spring, and consequently the tension upon the shuttle-thread, may be varied.

The shuttle-shell (see Fig. 5) has connected with it a spring hook or latch 67, which engages a notched or beveled part of the lid and holds the latter closed.

The shuttle described is placed in a shuttle-race D', having a circular cavity, and is held therein by a cap, as D², attached thereto by suitable screws. (Best shown in Fig. 3.) The said shuttle-race has a shoulder, which receives against it one side of the projection 56 at the periphery of the shuttle, the other side of the said projection being acted upon by the cap or cover D². The shuttle-race contains a shuttle-carrier, as D³, it having two projections, as 68 69, the projection 69 acting upon the shuttle near its heel, while

the projection 68, cylindrical in shape, enters the nearly-circular space 70 at the base of the beak 52 of the shuttle, the projection 69 acting as a driver to move the shuttle through the loop of needle-thread, the projection 68 acting to return the shuttle to its starting-point.

The lid 59 of the shuttle is provided with a raised projection 59^x, which is extended to the base of the beak 52 and receives upon it the loop of needle-thread.

The shuttle-carrier referred to is attached to an oscillating shaft D⁴, provided at its rear end with a pinion 71, (shown best in Fig. 2,) which is engaged and oscillated by a series of beveled teeth constituting a rack and carried at the forward bent end of a shuttle-actuating lever D⁵, having its fulcrum at D⁶, the said lever between its ends having a roller or other stud 72, (shown by dotted lines, Fig. 7,) which enters a cam-groove 72^x, (shown, also, by dotted lines in said figure,) formed at the left-hand side of the cam-hub *d*, the said cam-groove moving the said shuttle through an arc of about two hundred and seventy degrees, more or less.

The shuttle-carrier has attached to it by a screw, as 73, a pad, as 74, preferably made of sheet-steel, the said pad being so shaped as to act upon that part of the needle-thread located between the shuttle and carrier, and through which the shuttle is being then moved, the pad so clamping or holding that portion of the loop of needle-thread that the other part of the loop, when cast off from the heel of the shuttle by the take-up, will not be pulled back through the material by the friction of one portion of the loop against the other portion, thus forming slack in the thread between the stitch being set and the previous stitch.

The head of the machine has bolted to it at r' a loop-guide r², (see Figs. 3 and 4,) upon which drops the loop of needle-thread as it is cast off from the heel of the shuttle, the said guide being so shaped or inclined toward the stock as to somewhat detain or guide the said loop while it is being drawn up by the take-up and keep it out of the way of the needle.

In Fig. 3 we have shown the loop of needle-thread as upon the guide r² and in the act of being drawn down and off from the said guide.

We do not herein broadly claim the combination, with a curved hooked needle and a curved feeding-awl, of an oscillating shuttle; nor do we claim anything shown in United States Patent No. 366,935.

We are aware that prior to our invention a tension device employed in a wax-thread sewing-machine has been acted upon and held while the take-up operated to take up the stitch; but we are not aware that the said thread has been acted upon directly, as herein described, by a clamp to hold it intermittently between the thread-supply and the take-up; nor are we aware that a pull-off has

been used in a wax-thread machine to operate with a yielding work support and clamp, such as described, to pull off a variable amount of thread for a stitch to be made.

5. We claim—

1. In a wax-thread sewing-machine, the following instrumentalities, viz: a work-support, an oscillating curved hooked needle, a looper to supply it with thread, a curved awl, a shuttle-race, a substantially circular shuttle therein, a take-up, a clamp to act directly upon the needle-thread on its way to the take-up, a pull-off to act upon the needle-thread between the said clamp and the thread-supply, and means actuating the said clamp and pull-off, whereby the clamp acts to hold the needle-thread between the pull-off and the take-up, while the pull-off acts to draw from the thread-supply a sufficient quantity of needle-thread for the next stitch to be made, substantially as described.

2. In a wax-thread sewing-machine, the following instrumentalities, viz: a work-support, an oscillating curved hooked needle, a looper to supply it with thread, a curved awl, a shuttle-race, a substantially circular shuttle therein, a take-up, a clamp to act directly upon the needle-thread on its way to the take-up, a pull-off to act upon the needle-thread between the said clamp and the thread-supply, and means actuating the said clamp and pull-off, whereby the clamp acts to hold the needle-thread between the pull-off and the take-up, while the pull-off acts to draw from the thread-supply a sufficient quantity of needle-thread for the next stitch to be made, and an auxiliary take-up, to operate substantially as described.

3. In a wax-thread sewing-machine, the following instrumentalities, viz: a circular shuttle-race, a substantially circular shuttle therein, a curved hooked needle, a thread-guide, a looper to supply it with thread, a take-up to act upon the needle-thread, means to actuate the take-up, a curved awl, means to actuate the said needle and awl, a channel-guide to retain the stock at a predetermined level as the needle enters it for each stitch, a thread-clamp to act directly upon the needle-thread between the thread-supply and the said take-up, a yielding work-support, a pull-off to act directly upon the needle-thread between the thread-clamp and the thread-supply, and variable-motion devices intermediate and connecting the said yielding work-support on which the work rests with the said pull-off, whereby as the work-support rises and falls, owing to variations in the thickness of the stock upon it, the said pull-off will have given 60 to it automatically a variable throw, to thereby adapt the length of the loop of needle-thread to the thickness of the stock, substantially as described.

4. In a wax-thread sewing-machine, the curved hooked needle, the yielding work-support, a pull-off consisting, essentially, of a lever having a roll and a sliding shoe mounted upon one arm of the said lever, combined with an adjustable connecting rod or link joined at one end to the said shoe and at its other end to the said work-support, to operate substantially as described.

5. In a wax-thread sewing-machine, the yielding work-support, the curved hooked needle, and a clamp consisting of a bar, as 5, and rolls 3 4, located at opposite sides the said bar to clamp the needle-thread, a pull-off to act upon the needle-thread between the said clamp and the thread-supply, and connecting devices between the pull-off and the said yielding work-support, combined with means to automatically operate the said clamp, substantially as described.

6. In a wax-thread sewing-machine, the yielding work-support, the curved hooked needle, and a clamp consisting of a bar, as 5, and rolls 3 4, located at opposite sides the said bar to clamp the needle-thread, a pull-off to act upon the needle-thread between the said clamp and the thread-supply, and connecting devices between the pull-off and the said yielding work-support, combined with means to automatically operate the said clamp, and with the auxiliary take-up, to operate substantially as described.

7. In a wax-thread sewing-machine, the curved oscillating hooked needle and the looper having a hollow shank and upwardly-extended arm o' , and bearings for the said shank, combined with gear o^{14} , the segmental lever o^{17} , the lever o^9 , link o^8 , and with means to actuate said levers to not only reciprocate the said looper, but to also impart a slight rocking motion thereto, substantially as described.

8. In a wax-thread sewing-machine, the yielding work-support, the curved hooked needle, a take-up for the needle-thread, a shuttle, and a shuttle-race therefor, combined with a loop-guide, as r^2 , located between the shuttle-race and the said work-support and having its delivery end terminating near the upper side of the stock being sewed, the said loop-guide receiving upon it and guiding the loop of needle-thread as it is discharged from the shuttle and during the time the loop is being drawn down to the work by the take-up, substantially as described.

In testimony whereof we have signed our names to this specification in the presence of two subscribing witnesses.

ZACHARY T. FRENCH.
WILLIAM C. MEYER.
